W. B. SMITH,
POCKETED RECEPTACLE,
APPLICATION FILED SEPT. 5, 1916.

Patented May 22, 1917.

Inventor:
William D. Smith.
By G. L. Gragg Atty.

UNITED STATES PATENT OFFICE.

WILLIAM B. SMITH, OF CHICAGO, ILLINOIS.

POCKETED RECEPTACLE.

1,226,919.

Specification of Letters Patent. Patented May 22, 1917.

Application filed September 5, 1916. Serial No. 118,488.

To all whom it may concern:

Be it known that I, WILLIAM B. SMITH, citizen of the United States, residing at Chicago, in the county of Cook and State of Illinois, have invented a certain new and useful Improvement in Pocketed Receptacles, of which the following is a full, clear, concise, and exact description, reference being had to the accompanying drawings, forming a part of this specification.

My invention relates to pocketed receptacles. One feature of the invention pertains particularly to a structure which includes a backing, a longitudinally adjustable pocket forming strip acting in conjunction with the backing to form pockets, and a plurality of pressure exerting clamping members operable toward and from the backing and adjustable longitudinally of the backing for locking selected portions of the pocket forming strip and backing in fixed engagement to provide pockets of fixed sizes. In adapting this feature of my invention to a pocketed receptacle of the class described the pressure exerting clamping members are mounted upon carriers that extend transversely of the pocket forming strip, these pressure exerting or clamping members being engageable with the pocket forming strip. Said pressure exerting or clamping members are desirably in the form of screws in threaded engagement with the carriers, these screws having knurled heads by which they may be turned in their carriers to bring them into abutting engagement with the pocket forming strip that is interposed between the screws and the backing. By this arrangement sufficient material of the pocket forming strip may be clamped in place with reference to the backing and the carriers are held in fixed relation to the backing. I thus simplify the structure illustrated in my United States Letters Patent 1,134,561, dated April 6, 1915.

Another feature of my invention relates to improved means for taking up the excess or slack that is left in the pocket forming strip after the pockets are formed and while I desirably practice this feature of my invention in conjunction with a structure that includes a plurality of pressure exerting or clamping members, I do not wish to be limited to the embodiment of both features of the invention in the same structure. In carrying out this additional feature of the invention, one end of the pocket forming strip

is desirably fixedly anchored with relation to one end of the backing, the pocket forming strip passing from this anchored end over the backing and beneath the backing, the free end of the pocket forming strip being continued preferably in the form of a string whereby the excess or slack in the pocket forming strip may be pulled beneath the backing, the string desirably being secured to an anchorage after the slack has been taken up.

I will explain my invention more fully by reference to the accompanying drawing showing the preferred embodiment thereof and in which Figure 1 is a front or plan view of a structure made in accordance with the invention (some parts being broken away) the contents for the pockets being also illustrated in this figure; Fig. 2 is a view on line 2—2 of Fig. 1; Fig. 3 is a view on line 3—3 of Fig. 2; and Fig. 4 is a perspective view of a carrier and two clamping members upon the same, there being desirably two such members to each carrier.

Like parts are indicated by similar characters of reference throughout the different figures.

The strip *a* of flexible material of which the pockets are to be made may be of any suitable thin material such as leather, split leather, or some textile fabric, this strip being longitudinally adjustable to adapt it to the formation of pockets of differing sizes. The strip *a* may be anchored at one end by means of stitches *b* to a backing *c* whose longitudinal edges are shown as being secured to a board *d* by means of rows of stitches *e*. The board illustrated includes a sheet of pasteboard or fiber board *f* which is covered by textile lining *g*. The top layer of this lining is slit, as indicated at *h*, at the other end of the backing *c* from where the pocket forming strip is anchored by the stitches *b*. The portion of the lining *g* which underlies the backing *c* is desirably loose from the stiffening sheet *f* so that the pocket forming strip may pass through the slit *h*, beneath the loose portion of the lining *g*, thence out through the slit *i* occurring slightly beyond the stitching *b* that fixedly anchors one end of the pocket forming strip to the backing, as hitherto set forth. The portion of the pocket forming strip that is not required to form the pockets is drawn beneath the backing and in order

that this portion or slack may not be drawn above the backing the end of the pocket forming strip that passes between the loose portion of the lining *g* and the stiffening board *f* is anchored. In the preferred embodiment of the invention the pocket forming strip is provided with a continuation that is in the form of a string *k* which may be tied or otherwise secured to a tab *l* or other anchorage means that is provided upon the board *d*.

The means described for taking up the slack in the pocket forming strip is desirably employed in conjunction with my improved means for holding fixed portions of the pocket forming strip in relation to the backing to form pockets for holding articles such, for example, as the brush *m*, the safety razor outfit *n*, the tooth brush *o* and the comb *p*, though these two features of the invention are not to be limited to association with each other. In practising the feature of my invention now being described, the longitudinal edges of the backing *c* project appreciable distances beyond the rows of stitching *e*, as indicated at *c'*, *c''*. The clamp carriers *q* are in the form of bars extending transversely of the pocket forming strip *a*, the ends *r* of the bars being inturned to project beneath the longitudinal portions of the backing *c* that project beyond the rows of stitching *e* and which projecting portions of the backing freely overhang the board *d*. This arrangement permits the clamp carriers *q* to be moved lengthwise of the backing when the clamping screws *s* carried thereby are withdrawn from clamping engagement with the pocket forming strip *a*, but when these clamping screws are screwed down upon the strip *a* the inturned ends *r* are pressed outwardly upon the underneath sides of the overhanging portions *c'* of the backing *c*. The clamping screws thus perform the double function of holding the pocket forming strip *a* tightly against the backing and of drawing the clamp carriers *q* into tight engagement with the backing at the ends *r* so that the clamp carriers cannot then be moved longitudinally of the backing.

In one way of using the device the right hand pocket is first formed to hold an article such as the comb *p*, this article being located between the backing *c* and the pocket forming strip *a* whereafter the adjacent clamping devices and the carriers therefor are suitably adjusted with relation to this article, the screws *s* being turned into forceful engagement with the pocket forming strip upon both sides of the article to fix the extent of the portion of the pocket forming strip that is to hold the article and to hold the carriers for the screws in the positions to which they are adjusted. The second article, such as the tooth brush *o*

is next interposed between the pocket forming strip *a* and the backing *c* whereupon the third clamping carrier and the clamping screws thereupon are suitably adjusted with respect to the intermediate clamp carrier in the manner and for the purpose previously stated. In like manner the remaining pockets are formed with the exception that the pocket holding the last article *m* need not be provided with clamping means to the left thereof, the left hand end of the carrier *c* serving to define the extent of the portion of the pocket forming strip that is to form the pocket for the article *m* when the pocket forming strip passes beneath the backing *c* and is anchored to the tab *l* as hitherto described. If preferred, however, clamping means may be provided to the left of the article *m* as in the case of each of the other articles *n*, *o*, *p*.

While I have herein shown and particularly described the preferred embodiment of my invention I do not wish to be limited to the precise details of construction shown as changes may readily be made without departing from the spirit of my invention but having thus described my invention I claim as new and desire to secure by Letters Patent the following:

1. A pocketed receptacle including a backing having overhanging longitudinal edge portions; a longitudinally adjustable pocket forming strip acting in conjunction with the backing to form pockets; a plurality of pressure exerting clamping screws; carriers for these screws having inturned ends projecting beneath said overhanging portions of the backing so as to be adjustable longitudinally of the backing, said screws having threaded engagement with said carriers and being in position to engage the pocket forming strip to force this strip against the backing and to press the inturned ends of the carriers against the backing.

2. A pocketed receptacle including a backing; a longitudinally adjustable pocket forming strip acting in conjunction with the backing to form pockets; a plurality of pressure exerting clamping screws operable toward and from the backing and having engagement therewith to press selected portions of the pocket forming strip against the backing to form pockets of selected sizes; and carriers for the clamping screws adjustable longitudinally of the backing and engageable therewith, said clamping screws, in addition to pressing the selected portions of the pocket forming strip against the backing, also operating to press said carriers against the backing to hold them in selected adjustment.

3. A pocketed receptacle including a backing; a longitudinally adjustable pocket forming strip acting in conjunction with

the backing to form pockets; a plurality of pressure exerting clamping members operable toward and from the backing and having engagement therewith to press selected portions of the pocket forming strip against the backing to form pockets of selected sizes; and carriers for the clamping members adjustable longitudinally of the backing and engageable therewith, said 10 clamping members, in addition to pressing

the selected portions of the pocket forming strip against the backing, also operating to press said carriers against the backing to hold them in selected adjustment.

In witness whereof, I hereunto subscribe 15 my name this 13th day of July A. D., 1916.

WILLIAM B. SMITH.
